UNITED STATES PATENT OFFICE.

MORRIS J. HOFFMAN, OF CHICAGO, ILLINOIS.

COUPON-REGISTER.

1,119,698.

Specification of Letters Patent.

Patented Dec. 1, 1914.

Application filed May 23, 1914. Serial No. 840,583.

To all whom it may concern:

Be it known that I, MORRIS J. HOFFMAN, a citizen of the United States, and a resident of Chicago, county of Cook, and State of Illinois, have invented certain new and useful Improvements in Coupon-Registers, of which the following is declared to be a full, clear, and exact description.

This invention relates to coupon registers and has for its primary object to provide a simple form of register for indicating the amount of work done by employees in various lines of industry.

The present register has been particularly designed for use in the tailoring industry, where a large number of operatives are employed to perform labor upon each garment, each operative doing certain work on a garment and receiving therefor a stipulated amount. One method of keeping record of the work done is to provide a coupon ticket with each garment, one coupon being intended for each operative and bearing a mark designating that person, and each operative tears off and retains the coupon intended for him, after he has completed his work upon the garment, and at the close of the day or other predetermined time presents the coupons to a timekeeper and receives credit therefor. In many establishments 50,000 or more coupons are thus handled daily and it is an irksome, and tedious task to count the coupons and frequently errors creep in so that the operatives are paid more than they should receive and sometimes less, thus causing friction and annoyance. With my present invention the coupons are registered or accounted for the moment they are placed in the register so that there can be no mistake and all of said difficulties are wholly avoided.

The invention is clearly illustrated in the drawings accompanying this specification, in which:

Figure 1 is a perspective view of a pair of registers embodying the preferred form of the invention; Fig. 2 is a cross section taken through one of the registers seen in Fig. 1; Fig. 3 is a fragmental longitudinal section taken on the line 3—3 of Fig. 2; Fig. 4 is a fragmental face view of a coupon ticket used in connection with the register; Fig. 5 is a side view of a canceling roller which may be used in connection with the register; Fig. 6 is a perspective view of a modified form of register; Fig. 7 is a cross section taken through the register seen in Fig. 6; and Fig.

8 is a perspective view of a fragment of the register seen in Fig. 6.

Referring to said drawings, the first Figs. 1 to 4, inclusive, A, A, designate two of the registers embodying the preferred form of the invention, and as shown each comprises a box 10, having a bottom 11, top 12, sides 13, and ends 14. Preferably, the sides 13, are slotted to provide large central openings 15, therein, and said sides converge toward each other from top to bottom, for reasons that will appear later on. The top 12, of the register is provided with narrow openings 16, extending transversely across the top and preferably arranged in series or groups of ten openings each, separated by space bars 17. If desired the groups or series of openings may be arranged in a plurality of rows 75 as shown in Fig. 1 and at the end of each series is a designating numeral or number indicating the number of openings preceding the numeral. For convenience I have shown 50 openings in each row and two 30 rows in each register, making a total of 100 openings. In cases where an operative performs work upon more than 100 garments a day, two or more registers may be used and if desired they may be secured together, as 85 for instance, by solder 18, or in any other convenient manner.

The tickets 19, (see Fig. 4) are usually in the form of long strips of card board scored transversely to provide coupons 20, each 90 bearing the identification number of the garment (indicated at 21) and also the identification numbers of the persons operating upon said garment, as indicated at 22. The first person to work upon the garment and 95 whose identification number may be No. 1, tears off coupon No. 1 and inserts it in the first opening of the register allotted to him, and the second operative does likewise. Each operative does the same with respect to all 100 of the garments upon which he performs any work, and if any operative does any additional or other work for which there is an extra charge, he may use two registers, placing in one the coupons for ordinary 105 work, and in the other, the coupons for the other grades of work. At the end of the day the registers are given over to the time-keeper, who, may at a glance observe the total number of coupons contained in the 110 register and thus give the operative credit therefor. It is to be noted that the coupons project beyond the openings so that any authorized person, for instance the time-

keeper, may, by running his finger over the upper edges of the coupon, bend them over and observe each one so as to detect any spurious ones in case they have been inserted in the register.

A roller B (see Fig. 5) may be used at the close of the day for canceling the coupons by running the same over them, while held in the register. This roller may be used in connection with an ink pad or may have sharp points thereon for perforating the coupons.

Preferably the register thus far described is made of sheet metal and the openings are formed by slitting and punching the metal inwardly to form slots, and this leaves sharp edges at the lower sides of the slots, which act in a measure to prevent the coupons from accidentally falling out of the register. By providing the box with the downwardly converging sides 13, the lower ends of the coupons of one row overlap the lower ends of the coupons of the other row as seen in Fig. 2 and in a measure prevent the coupons from falling out of the register. The large openings in the sides of the register provide entrances to the interior thereof whereby a person may observe the lower ends of the coupons in the register and also may insert a pencil or other object to remove any that may have fallen into the hollow of the box.

In the form shown in Figs. 6 to 8, inclusive, the slots or openings 16^a, are provided upon thin, flat, card-board backs or other pieces of suitable material hingedly secured together at 28, in the manner of ordinary book covers, whereby the two portions may be folded and secured together or laid out flat. In this case transparent strips 24 are employed to form pockets for the reception of the coupons 20, and said transparent strips may comprise celluloid strips or the like and are stitched to the back piece or cover along longitudinal lines 25, and also along transverse lines 26, the edge 16^b of each strip overlying the stitched edge 25 of the strip below. The pockets are designated by numbers running in regular numerical progressions from 1 and upward, and with this form of register the operator inserts the coupons in the pockets, beginning at the pocket designated as No.

1. In each case the numbers designate the pockets in the row beyond them and nearer the center of the device, so that when the first coupon is inserted in the first pocket it covers up the number appearing underneath it, the part of the coupon in the pocket, however, being visible to view so that the entire coupon can be seen and spurious ones detected. With this modified form the time-keeper or other authorized person may ob-

serve at a glance how many coupons are contained in the register, because the last 65 coupon inserted and all of those inserted prior to it cover the designating numbers of those pockets and the next higher number will be exposed to view.

I claim as new and desire to secure by 70 Letters Patent:

1. A coupon register of the character described, having a side provided with a plurality of slots or slits therein through which coupons, bearing indicating characters, may 75 be inserted and temporarily retained by the register, certain of said slots or slits having coupon indicating numbers printed adjacent thereto and arranged in numerical order or sequence, each indicating number being in 80 position to be covered by a coupon when inserted in an adjacent slot or slit whereby the total number of coupons inserted in the register may be ascertained by glancing at the last coupon inserted, and observing the exposed 85 coupon indicating-number adjacent thereto.

2. A coupon register of the character described, having a side provided with a plurality of coupon receiving portions for holding coupons, bearing indicating characters, said coupon receiving portions having numbers printed adjacent thereto for indicating the total number of coupons received by the register, and each indicating number 95 being in position to be covered by a coupon when attached to an adjacent coupon receiving portion, whereby the total number of coupons received by the register may be ascertained by glancing at the last coupon received and observing the adjacent exposed 100 coupon indicating number.

3. A coupon register of the character described, comprising a coupon receiving element having a plurality of slits in one side 105 for receiving coupons bearing indicating characters, said slits being arranged parallel to each other, and there being indicating numbers printed in the spaces adjacent the slits, each number being arranged to be covered by a coupon when inserted in a corresponding slit, whereby the total number of coupons in the slits may be ascertained by glancing at the last coupon inserted, and noting the exposed number at the adjacent 115 slot.

4. A coupon register having a flat side, adapted to receive and return a plurality of coupons, and a canceling roller capable of being rolled over said coupons for the purpose specified.

MORRIS J. HOFFMAN.
